UNITED STATES PATENT OFFICE

154,484

DESIGN FOR AN ELECTRIC POPCORN POPPER

Charles B. Hobbs, Decatur, Ill., assignor to U. S.
Manufacturing Corporation, Decatur, Ill., a
corporation of Illinois

Application May 5, 1948, Serial No. 146,171

Term of patent 14 years

(Cl. D81—10)

To all whom it may concern:

Be it known that I, Charles B. Hobbs, a citizen of the United States of America, residing at Decatur, in the county of Macon and State of Illinois, have invented a new, original, and ornamental Design for an Electric Popcorn Popper, of which the following is a specification, reference being had to the accompanying drawings, forming a part hereof.

Fig. 1 is a top plan view of an electric popcorn popper showing my new design; and

Fig. 2 is one side elevation thereof, the other side being substantially like the side illustrated.

I claim:

The ornamental design for an electric popcorn popper, as shown and described.

CHARLES B. HOBBS.
